BAND-BRAKE.

1,108,851.

Specification of Letters Patent. Patented Aug. 25, 1914.

Application filed August 30, 1911. Serial No. 646,778.

To all whom it may concern:

Be it known that I, ANDREW L. RIKER, a citizen of the United States, and a resident of Bridgeport, county of Fairfield, State of Connecticut, (whose post-office address is Bridgeport, Connecticut,) have invented an Improvement in Band-Brakes, of which the following description, in connection with the accompanying drawings, is a specification, like characters on the drawings representing like parts.

This invention relates to band brakes, being more particularly intended to provide means for freeing a band brake from its drum when unclasped therefrom.

The invention will be best understood by reference to the following description when taken in connection with the accompanying illustration of one specific embodiment thereof, while its scope will be more particularly pointed out in the appended claims.

In the drawings: Figure 1 is a central, sectional elevation taken through a brake drum and band brake embodying one form 25 of my invention; and Fig. 2 is a detail in section taken on the line 2--2 in Fig. 1.

Referring to the drawings and to the embodiment of the invention there disclosed, for illustrative purposes I have shown the 30 same embodied in the form of an automobile brake, the same comprising primarily the brake drum 1 mounted on the drum shaft 2 encircled by the brake band 3, having the usual lining 4 of friction material. Any usual 35 means for clasping the band about the drum are provided, the same being herein shown to consist of the bell crank lever 5 pivotally connected to one end of the band and the link 6 pivoted to the other end. The lever 40 5 is forked and has pivoted therein a block 7 through which the link 6 passes, the end of the link being threaded and having applied thereto the lock nut 8. A spring 9 encircling the link tends to separate the ends 45 of the band, but the latter may be applied by a movement of the actuating rod 10 jointed to the end of the bell crank lever 5. In brakes of this class it is difficult to free the entire, or even the major part, of the 50 50 brake band from the drum when its ends are opened by the releasing devices. On the other hand, if devices are employed for freeing intermediate parts of the brake band from the drum, such devices usually interfere with the utilization of the entire extent

of the band for braking purposes and in the case of automobile brakes frequently present loosely attached supports which add to the noise and rattle of the machine when on the road.

Herein I have provided means for freeing the parts of the band intermediate the ends from the brake drum when the brake is released, while at the same time admitting the utilization of substantially the entire band for braking purposes, such means, however, being preferably of such a nature that substantially all rattle and shake is eliminated upon the road.

Referring to the drawings, the band 3 is connected at two points intermediate its ends to curved resilient members 11. The latter might be separate each from the other, but preferably, as herein, they constitute two arms of a unitary curved leaf spring, the mid portion of which is riveted or otherwise secured to a fixed support such as the shoe 12, the latter being fixed to the part 13 which herein is presented by a fixed part of the machine such as the distance bar 14. The shoe is preferably, though not necessarily, located at a point substantially 180° from the ends of the band and the spring arms 11, which are curved to embrace the band for a substantial distance, herein 85 approximately its semi-circumference, are preferably connected thereto only at their ends so as to leave the intermediate portion of the band free and detached. The end of each spring arm is secured to a bolt 15 passing through lugs 16, the latter riveted or otherwise secured to the sides of the brake band 3.

When the ends of the band are clasped about the drum the spring arms move inward with a readily yielding movement, permitting the band clasping devices to draw the band into frictional contact with the drum for its entire circumferential extent. The support offers substantially no obstruction to contact of the band with the drum at points intermediate the ends of the spring arms as is the case with brake band supports which held the center of the band in fixed position. On the other hand the resiliency 100 of the arms is such that when the band is unclasped the springs tend to open. The resultant movement of the ends of the arms is both outward and backward, that is to say, the band is not only drawn slightly away 110

from the drum at the points where the spring ends are attached so as to free the band thereat, but these points of the band are also shifted slightly toward and in the direction of the fixed support 13 so that all intermediate parts of the band are likewise freed from the drum. A very slight freeing movement of the band only is required and, to accomplish this, the spring arms need execute but a very small movement.

It will be observed in the form of the invention illustrated that the spring arms 11 not only serve to free the band from the brake drum, but constitute the anchor or support for the band which holds it in established relation to the drum.

In employing the term band brake, I, of course, include all such devices as are adapted to encircle and apply friction to a rotating body whether strictly in the form of bands, and in using the term drum, I include all such rotating bodies whether or not they have the geometrical characteristics of a true drum.

While I have herein shown and described one specific embodiment of the invention, it is to be understood that the same is submitted for the purposes of illustration, and extensive deviations from the form described herein may be made, as well as from the application made thereof, without departing from the true spirit of the invention.

Claims.

1. The combination with a brake drum of a band brake encircling the same, means engaging the ends of the band for clasping the same about the drum, and intermediate band freeing means comprising a member in the form of a leaf spring fixed at its middle at a point substantially 180° from the ends of the band and curved to embrace the band for substantially its semi-circumference, the ends of the spring being connected to the band and the intermediate part thereof being detached therefrom.

2. The combination with a brake drum of

a band brake encircling the same, band clasping means, and intermediate band attachment means comprising a curved spring member encircling substantially one-half of the band and having its ends connected thereto, said spring member being secured to a fixed support at an intermediate point.

3. The combination with a brake drum of a band brake encircling the same, band clasping means, and band freeing means comprising a fixed support intermediate the ends of the band, a curved resilient member secured to said support but extending therefrom to partly encircle the band, said support being attached to said band to free the latter when unclasped.

4. The combination with a brake drum 1 of the band brake 4, the resilient arm 11 having the connection 15—16 to the brake 65 band, and the fixed support 13.

5. The combination with a brake drum of a band brake encircling the same, band clasping means, and means connected to two separated points of the band to free the intermediate part thereof from the drum, said means comprising resilient members having each a fixed end and a connection to the band and serving as the anchor or support for the band.

6. The combination with a brake drum of a band brake encircling the same and band-freeing and anchoring means comprising a fixed support intermediate the ends of the band, a curved resilient member secured to said support but extending therefrom to partly encircle the band, said support being attached to said band to anchor and support the same but to free the band when unclasped.

In testimony whereof, I have signed my name to this specification, in the presence of two subscribing witnesses.

ANDREW L. RIKER.
